United States Patent Office

Des. 190,718
Patented June 27, 1961

190,718

BOOT

Sidney Cohn, 1020 Crossland Ave., Clarksville, Tenn.

Filed Apr. 8, 1960, Ser. No. 60,091

Term of patent 7 years

(Cl. D7—7)

Fig. 1.

Fig. 2.

Fig. 3.

Fig. 4.

Fig. 5.

I claim:

The ornamental design for a boot, as shown.
